FUEL VALVE

Charles W. Thornhill, Houston, Tex.

Application July 13, 1933, Serial No. 630,263

4 Claims. (Cl. 158—117.2)

This invention relates to fuel valves.

It has for its general object the provision of a new and improved fuel valve that will be found particularly useful in connection with gas burners to permit the flow of gas to the burner so long as the latter is burning and to automatically shut off the flow of gas to the burner should the flame be extinguished.

A specific object of the invention is to provide in a valve of this type a pair of relatively movable elements, the one being connected to a latching device whereby it may be held open to permit the flow of the gas to the burner initially, and the other being connected to a thermostatic element arranged to be expanded by the heat generated by the burner to permit the continued flow of the gas and to render the latching means inoperative so that when the flame is extinguished the contraction of the thermostatic element will effect a predetermined movement of said elements to shut off the flow of the gas.

Another specific object is to provide in such a valve new and improved packing means for the valve element rods arranged to be compressed by the springs utilized to actuate said elements.

Another specific object is to provide new and improved adjustable means to render the valve usable with thermostatic elements of various sizes.

A further object is to utilize the burner itself as a thermostatic element to operate the valve.

Other objects will hereinafter appear.

The preferred embodiments of the invention are illustrated by the accompanying drawing wherein Fig. 1 is a top plan view of one embodiment; Fig. 2 is a detail view showing the details of the valve in the embodiment shown by Fig. 1; Fig. 3 is a detail view illustrating the adjustable means whereby the valve may be used with thermostatic elements of various sizes; Fig. 4 is a sectional elevation of another modification; and Fig. 5 is a partly sectional fragmentary elevation of a further modification.

It will be understood that while the invention will be found particularly useful in connection with gas burners, it may be used with any fuel apparatus.

Referring to Figs. 1 and 2 of the drawing, the gas inlet pipe is indicated at 1, the valve body at 2 and the burner at 3. Adjacent the burner 3 is a thermostatic element 4 which may comprise a metal ribbon adjustably connected at one end by the nut 5 to the bracket 6 and at the other to the rod 7 of the first valve element 8. The thermostatic element 4 may be connected to the rod 7 by the connection indicated at 9.

The first valve member 8 is adapted to cooperate with the seat 10 in the valve body from which it is normally urged by the compression

spring 11 bearing thereagainst and against the plate 12 to compress the packing 13.

The first valve element 8 has openings 14 therein which are normally closed by the second valve element 15 which has a rod 16 extending through the valve body 1 and having pivoted at 17 to its outer end the latch 18. The second valve element 15 is urged upon the first valve element 8 to close the openings 14 by the spring 19 bearing thereagainst and against the plate 20 to compress the packing 21.

The first and second valve elements 8 and 15 are preferably in the form of disc-like diaphragms as shown.

The operation of this embodiment is as follows:

The operator, grasping the latch 18, pulls the rod 16 outwardly against the resistance of spring 19 to move the second valve element 15 away from the first valve element 8; and rotates the latch 18 on its pivot 17 to cause the cam surface 18—a to bear against the body 1 and releasably hold the parts in said positions.

Gas may thereupon pass through the openings 14 in the first valve element 8 and through pipe 1 to the burner 3. Gas is then ignited to perform any desired function. The thermostatic element 4 has been adjusted by the means 5 so that it is under tension to hold the first valve element 8 upon the seat 10 against the resistance of spring 11. The heat generated by the burning gases at the burner 3 expands the thermostatic element 4 to permit the spring 11 to move the first diaphragm 8 into engagement with the second diaphragm 15 to actuate the latter and thereby effect separation of the cam surface 18—a and the body 2 to permit the latch 18 to swing into its inactive position. The movement of the first valve element 8 by the spring 11 is limited by the hook 9 which constitutes a connecting means between the rod 7 and thermostatic element 4. As the spring 11 is stronger than the spring 19, the parts then remain in said positions so long as the gas continues to burn at the burner 3, the gas then passing between seat 10 and the first valve element 8.

Now if the gas at the burner be extinguished, the thermostatic element will contract to move the first valve element 8 upon its seat 10 against the resistance of spring 11; and the second valve element 15, actuated by the spring 19, will follow the first valve element 8 to close the opening 14. The flow of gas is thereby shut off.

Referring to Fig. 3, the numeral 22 indicates a rod corresponding to the first valve rod 7 just described. Instead of being connected directly to the thermostatic element 4 it is connected to an arm 23, pivoted at 24 on the bracket 25 which is mounted on the body 2. The thermostatic element 4 is connected by a pin 26 to the arm 23, and the arm 23 is provided with spaced openings

so that the pin 26 may be placed at various distances from the pivot 24. This adjustable means compensates for varying movements of different thermostatic elements 4 so that when the 5 thermostatic elements 4 are changed the actuation of the valve element rod 22 will be the same.

Referring now to Fig. 4, the valve body is indicated at 27. The burner and thermostatic element 28 comprises a pipe adjustably connected to 10 the bracket 29 by the threads 30 and having openings 31, through which the gas issues to be ignited, and openings 32 through which the gas enters the pipe 28.

The first valve element 33 is mounted on the 15 pipe 28 and cooperates with seat 34. It has a central opening 35. The second valve element 36 has a rod 37 on which is mounted corresponding latching device 38. The second valve element 36 is urged upon the first valve element 33 to close the opening 35 by the spring 39 bearing thereagainst and against the plate 40 to compress the packing 41.

The operation of this embodiment is as follows:

25 The operator grasps the latch 38 and thereby pulls the rod 37 outwardly to move the second valve element 36 from the first valve element 33; and rotates the latch 38 on its pivot 42 to cause the cam surface 38—a to engage the body 27 to 30 releasably hold the parts in said positions, so that gas may pass through the body 27 and opening 35 in second valve element 33 and into the pipe 38 to be ignited at the openings 31. When the pipe 28 is heated by the burning gas at the openings 31, it expands to move the first valve element 33 from the seat 34 into engagement with the second valve element 36 to disengage the cam surface 38—a from the body 27 so that the latch 38 will fall into its inactive position. Gas will 35 then pass through the openings 32 into the pipe 28.

If the flames at the openings 31 should be extinguished, the pipe 28 will contract to move the first valve element 33 upon its seat 34. The first 40 valve element 33 will be followed by the second valve element 36 actuated by spring 39 to close opening 35. The flow of gas to the pipe 28 will be thereby shut off.

In Fig. 5 the construction is the same except 45 that the pipe 44 has no openings in it and another pipe 45, communicating with the pipe 44, is provided with openings 46 through which the gas issues to be ignited.

I claim:

50 1. The combination with a gas burner, of a valve comprising a body having a seat; a first valve element; a first spring to urge said first valve element away from said seat; a heat responsive element associated with said burner and connected under tension to said first valve element to normally hold said first valve element upon said seat; said first valve element having an opening therein; a second valve element; a second spring to urge said second valve element upon said first valve element to close said opening; and a latch accessible from the exterior of said body to releasably hold said second valve element away from said first valve element against the resistance of said second spring; said heat responsive element being expansible by the heat generated by said burner to permit said first spring to move said first valve element away from said seat and into engagement with said

second valve element to move said second valve element against the resistance of said second spring and thereby cause said latch to release said second valve element, so that said second valve element may close the opening in said first valve element when said first valve element is returned to said seat by said heat responsive element. 5

2. The combination with a gas burner, of a valve comprising a body having a seat; a first valve element; a first spring to urge said first valve element away from said seat; a heat responsive element associated with said burner connected under tension to said first valve element to normally hold said first valve element upon said seat; said first valve element having an opening therein; a second valve element; a second spring to urge said second valve element upon said first valve element to close said opening; and a latch accessible from the exterior of said body to releasably hold said second valve element away from said first valve element against the resistance of said second spring; said heat responsive element being expansible by the heat generated by said burner to permit said first spring to move said first valve element away from said seat and to cause said latch to release said second valve element, so that said second valve element may close the opening in said first valve element when said first valve element is returned to said seat by said heat responsive element. 20

3. The combination with a gas burner, of a valve comprising a body having a seat; a first valve element; a heat responsive element associated with said burner and operatively connected to said first valve element; said first valve element having an opening therein; a second valve element; a spring to urge said second valve element upon said first valve element to close said opening; and a latch accessible from the exterior of said body to releasably hold said second valve element away from said first valve element against the resistance of said spring; said heat responsive element being expansible by the heat generated by said burner to permit movement of said first valve element away from said seat and to cause said latch to release said second valve element, so that said second valve element may close the opening in said first valve element when said first valve element is returned to said seat by said heat responsive element. 30

4. The combination with a gas burner, of a valve comprising a body having a seat; a first valve element; a heat responsive element associated with said burner and connected to said first valve element to normally hold said first valve element upon said seat; said first valve element having an opening therein; a second valve element; a spring to urge said second valve element upon said first valve element to close said opening; and a latch accessible from the exterior of said body to releasably hold said second valve element away from said first valve element against the resistance of said spring; said heat responsive element being expansible by the heat generated by said burner to move said first valve element away from said seat and to cause said latch to release said second valve element, so that said second valve element may close the opening in said first valve element when said first valve element is returned to said seat by said heat responsive element. 55
